DISPLAY CARD HOLDER FOR MERCHANDISE

William Christian, Milford, Conn.

Application December 17, 1937, Serial No. 180,309

9 Claims. (Cl. 40—11)

This invention relates to new and useful improvements in display card holders for merchandise, and has particular relation to a holder for mounting price or display cards on merchandise in stores, such for example as in grocery stores and the like.

An object of the invention is to provide a simple and inexpensive means which can be easily and quickly applied to or removed from various articles, which will not deteriorate in use, and which will effectively hold a price or other card on an article of merchandise in such manner and position as to be clearly visible and yet not easily knocked down or blown down or away.

Other objects and advantages will become apparent from a consideration of the following detailed description taken in connection with the accompanying drawing wherein satisfactory embodiments of the invention are shown. However, it is to be understood that the invention is not limited to the details disclosed but includes all such variations and modifications as fall within the scope of the invention.

In the drawing:

Fig. 1 is a side elevational view showing the holder of the invention mounting a card on a can, the upper portion only of the latter being shown;

Fig. 2 is a similar view but at right angles to Fig. 1;

Fig. 3 is an elevational view showing a modified construction of holder mounting a card on a can, portions of which are broken away;

Fig. 4 is a view similar but at right angles to Fig. 3;

Fig. 5 is a view similar to Fig. 1 but showing the device of the invention as applied to the mounting of a card on a bottle or the like;

Fig. 6 is a view taken at right angles to Fig. 5;

Fig. 7 is an enlarged plan view showing particularly the card receiving portion of my improved holder;

Fig. 8 is a side elevational view of the holder as shown in Fig. 7; and

Fig. 9 is a detail view showing a slight modification.

Referring in detail to the drawing and at first more particularly to Figs. 1, 2, 7 and 8 my improved holder generally designated 10 is shown as mounted on the upper portion of a can or the like 11, and supporting a card 12 in position above the top of the can. The holder 10 includes not only means for holding a card but also means whereby the holder is mounted on an article, as on the can 11. In making the holder a piece of wire, preferably a somewhat springy or resilient

wire, is bent upon itself at spaced points intermediate its ends to provide return bends 13 at each end of a curved portion 14 and a pair of curved arm portions 15 and 16 extending toward one another in substantially parallel relation to the portion 14.

The portions of the wire at the inner ends of the arm portions 15 and 16 are twisted together to provide a vertical substantially rigid shank 17 from the lower ends of which the end portions of the wire are carried laterally in opposite directions providing portions 18 and 19. The free ends of portions 18 and 19 are connected by a coil spring 20 which tends to draw such portions toward one another, and when the device is on a can as in Figs. 1 and 2 draws portions 18 and 19 against the sides of the can whereby the latter is gripped by said portions and by the spring and the card 12 properly supported. The spring 20 is somewhat stretched or tensioned when the holder is on a can or the like.

Portion 14 together with arm portions 15 and 16 provides a pair of curved arms extending laterally and downwardly in opposite directions from the stem or shank 17. Such arm portions include spaced substantially parallel members and the connecting end portions 13 at the lower outer ends of the arms. With particular reference to Figs. 1 and 8 it will be noted that the laterally extending arms are curved downwardly as they extend outwardly whereby the connecting portions 13 are not only their outermost portions but also their lowermost portions. The edge of card 12 is inserted between arm portions 14 and 15 and 16, and is held by the above mentioned arm portions acting jointly, and the lower edge of the card is supported at spaced apart points by resting on the connecting end portions 13 of the arms.

Thus the card is supported from rocking edge-wise in either direction and the card being partly between the side portions of the arms it is prevented from falling forward or backward. Moreover, due to their resilient action the side portions of the arms grip the card to prevent it blowing away or the like and hold it in proper position. However, if a relatively thick card is forced into the arms the sides thereof may be forced apart sufficiently so as not to come back to their original position when the card is removed and so might not properly hold a thinner card. If this should happen they can be brought back to their original position by squeezing them toward one another by gripping them with the thumb and finger adjacent the connecting portions 13 where-

by to bend them back into a close parallel relationship.

Referring now more particularly to Figs. 3 and 4 a card holder generally designated 21 is shown as mounting a card 22 on a container or the like 23. Holder 21 is also of wire and includes a shank 24 and the arm portions 14, 15 and 16 together with the connecting end portions 13 as in the case of the holder first described. Below 10 the shank 24 the wire of holder 21 has one of its ends bent laterally and then downwardly to provide an offset hook-like portion 25 designed to hook over the upper flange 26 of can 23 as shown, the edge of a cardboard, or other article. The 15 other end portion 27 of the wire is extended to lie along the side of the can 23 and to its free end is connected one end of a coil spring 28 to the other end of which is connected a hook-like member 29 designed to hook over the lower flange 30 20 of the can 23, or the lower edge of a cardboard, stiff paper, or other article.

Holder 23 supports the card 22 in the same manner as that described when referring to the holder 10 of the figures first described. In applying holder 21 to a container, such for example as the can 23, the hook 29 is engaged with the lower flange of the can and then by drawing upwardly to tension spring 28 the upper hook 25 may be passed over the upper flange of the can 30 leaving the spring 28 tensioned and thereby maintaining the hooks in overlapping relation with the can flanges. It will be seen this form can be used with cans or articles of any diameter and of various lengths. It also is not limited to 35 use on round cans or articles but is equally adapted for use on square cans or other shapes.

Figs. 5 and 6 show a construction the same as that of Figs. 1 and 2 with the exception that the holder of Figs. 5 and 6, generally designated 31, 40 is designed for use on bottles or other articles 32 having a small diameter neck portion, and therefore is provided with relatively short free end portions 33 and a relatively short coil spring 34. Otherwise the construction of Figs. 5 and 6 being 45 the same as that of Figs. 1 and 2 the same reference characters have been applied, and it will be understood that the card 35 of Figs. 5 and 6 is supported in the same manner as the card 12 first described.

From the foregoing it will be understood that the holder of the invention may be easily and quickly applied to and removed from cans, bottles and other articles of merchandise. Also it will be clear that the holder may be applied to a wide variety of shapes and sizes of articles. The holder may be transferred from one article to another, as it is but necessary to stretch the coil spring slightly in order to release the holder from any article. The card being held by the holder is in each instance held in such manner that it will not tilt unless forced to that position, and being gripped between the side portions of the arms of the holder will not be blown out of place by gusts of wind. Other resilient elements can be used in place of the springs 20, 55 28 and 34, such for example as an elastic rubber, but the metal spring is preferred as it does not deteriorate as a rubber would.

Any suitable means may be employed to connect the ends of the springs 20, 28 and 34 to the wires, a simple loop or eye being shown in Figs. 1 to 8. In Fig. 9 is shown a simple connection which permits easy adjustment of the spring on the wire to vary the size of the holder so as to be 70 able to use it for a larger number of devices. In

this arrangement the end of the wire 38 is bent upon itself as shown at 36 and then the free end 37 is bent outwardly to lie between adjacent convolutions of the spring 39. By relatively turning the spring and wire this free end travels along the spiral convolutions thus shortening or lengthening the effective length of the spring. This connection may be used at either end of the spring or both ends thereof as desired. The wire indicated at 38 having the bent portion 36 and 10 end 37 may be either one of the wires 18, 19, 21, 29 or 33 while the spring 39 may be either one of the springs 20, 28 or 34.

Having thus set forth the nature of my invention, what I claim is:

1. In a card holder, a wire having its intermediate portion bent upon itself to provide a pair of spaced portions connected at their outer ends and forming arms extending downwardly toward said outer ends, said portions adapted to 20 receive a card between them with the lower edge of the card resting on their connected end portions, said wire having its portions inwardly of its arm forming portions twisted together to form a shank, and a spring connected with the free 25 ends of such wire for securing it to an article.

2. In a card holder, a wire having its intermediate portion bent upon itself to provide a pair of spaced portions connected at their outer ends and forming arms extending downwardly toward 30 said outer ends, said portions adapted to receive a card between them with the lower edge of the card resting on their connected end portions, said wire having its portions inwardly of its arm forming portions twisted together to prevent casual 35 opening of the side portions of said arms and having its free ends extending in opposite directions, and a coil spring connected with the free ends of said wire for securing the latter to an article.

3. In a card holder, a wire having its intermediate portion bent upon itself to provide a pair of spaced portions connected at their outer ends forming arms, said portions curving downwardly toward their outer ends whereby such 45 ends are lowermost, said portions adapted to receive a card between them with the lower edge of the card resting on their connected end portions, said wire having its portions inwardly of its arm forming portions twisted together to prevent casual opening of said arm portions, and means for securing said wire to an article.

4. In a card holder, a wire having its intermediate portion bent to provide U-shaped oppositely directed arms the connecting portions of which are outermost, said arms extending downwardly toward their outer ends and adapted to receive a card between their side portions and resting on their connecting portions, said wire having its portions inwardly of said arms twisted 60 together to form an upstanding shank, and a coil spring connected with the free ends of said wire for securing it to an article.

5. In a card holder, a wire having its intermediate portion bent upon itself to provide a 65 pair of spaced portions connected at their outer ends and forming arms extending downwardly toward said outer ends, said portions adapted to receive a card between them with the lower edge of the card resting on their connected outer end 70 portions, said wire having its portions inwardly of its arm forming portions twisted together to form a shank, said wire having an end bent to overlie a flange of a container, a coil spring connected with the other end of the wire to be dis- 75

posed at the side of said container, and a hook also connected with said coil spring to hook over an opposite flange of the container.

6. A card holder of wire comprising a shank, outwardly and downwardly curved arms extending from opposite sides of said shank and each comprising spaced side portions and an outer end connecting portion whereby a card received between their side portions may rest on their connected outer end portions, and elastic means connected with said shank for securing the holder to an article.

7. A card holder comprising a wire twisted to form a shank, said wire at one end of the shank being bent to form members arranged side by side to receive the edge of a card between them and grip the card, the free ends of the wire at the other end of the shank extending in opposite directions, and a resilient member connecting the said free ends to clamp the holder to an article.

8. A card holder comprising a wire twisted to form a shank, said wire at one end of the shank

being bent to form members arranged side by side to receive the edge of a card between them and grip the card, a hook on said shank adapted to engage over a flange on an article, a second hook spaced from the first hook adapted to engage over another flange, and a resilient element between said hooks to retain them on the flanges.

9. A card holder comprising a wire forming a shank, said wire at one end of the shank being bent to form members arranged side by side to receive the edge of a card between them and grip the card, a portion at the other end of the shank being bent upon itself with its free end extending laterally outward, said shank also having means to engage an article, a spring embracing said bent end with said free end positioned between adjacent convolutions of the spring, and means connected to the other end of the spring to engage an article and cooperate therewith and said first means to secure the holder to the article.

WILLIAM CHRISTIAN.
